UNITED STATES PATENT OFFICE.

CHARLES H. WAYS, OF CONNELLSVILLE, PENNSYLVANIA.

DESIGN FOR A SOUVENIR SPOON.

SPECIFICATION forming part of Design No. 21,402, dated March 15, 1892.

Application filed February 13, 1892. Serial No. 421,490. Term of patent 3½ years.

To all whom it may concern:

Be it known that I, CHARLES H. WAYS, a citizen of the United States, residing at Connellsville, in the county of Fayette and State 5 of Pennsylvania, have invented and produced a new and original Design for Souvenir Spoons, of which the following is a specification, reference being had to the accompanying drawing, showing the same.

10 The drawing is a face view of the spoon, showing my design.

The leading or characteristic features of my design are the representation upon the upper enlarged extremity of the handle of a "larry" 15 resting upon the top of a coke-oven, and upon diminished portion of the handle of a coke-fork held by a hand-grasp, the tines of the

fork passing out into the bowl of the spoon. Upon the extreme lower tip of the spoon-bowl is shown a collection of "pile" of coke. Within 20 in the bowl, between the coke pile and the tines of the fork, is a panel upon which may be placed a suitable inscription or word.

Upon the drawing A represents the larry, B the coke-oven, and C the coke-fork, while 25 D represents the pile of coke.

What I claim is—

The design for a spoon, substantially as shown and described.

CHAS. H. WAYS.
